UNITED STATES PATENT OFFICE

2,478,137

REFRIGERANT LIQUEFYING UNIT

Albert J. Timmer, Dayton, Ohio, assignor to General Motors Corporation, Dayton, Ohio, a corporation of Delaware

Application November 2, 1946, Serial No. 707,361

10 Claims. (Cl. 62—115)

1

This invention relates to refrigerating apparatus and more particularly to an improved refrigerant liquefying unit.

The liquefying or condensing apparatus disclosed herein is primarily intended to be used with remotely located evaporators and is intended to be mounted out in the open rather than in a special machinery compartment of some refrigeration or air conditioning cabinet. Units of this type are usually sold separate from any cabinet or any evaporator coil and for that reason must be durable and at the same time should be lightweight so as to facilitate handling.

It is an object of this invention to provide a refrigerant condensing unit in which the condenser and the receiver are so constructed and arranged that there is no need for either a separate base or an outer casing.

More specifically it is an object of this invention to provide a low cost refrigerant condensing unit in which a stamped sheet metal receiver serves the dual purpose of a refrigerant storage tank and a base for the condenser and the motor compressor unit.

A further object of this invention is to provide a refrigerant condensing unit in which the condenser is supported directly by the receiver and in which the air circulating fan is in turn supported by the condenser so as to eliminate the need for expensive framework.

Further objects and advantages of the present invention will be apparent from the following description, reference being had to the accompanying drawings, wherein a preferred form of the present invention is clearly shown.

In the drawings:

Figure 1 is a vertical sectional view, partly diagrammatic, showing the relationship between the elements;

Figure 2 is a top view of the condensing unit with the top grill and a portion of the grill support broken away; and,

Figure 3 is a fragmentary perspective view showing the fin construction.

Referring now to the drawings wherein I have shown a preferred form of the invention, reference numeral 10 designates generally an annular-shaped receiver which constitutes the main support or base member for the condenser 12 and the motor-compressor unit 14. The receiver 10 comprises a pair of complementary metal stampings 16 and 18 which are hydrogen brazed to one another so as to form a refrigerant-tight tank. The upper stamping 18 has its edges flared as indicated in Figure 1 so as to facilitate assembly and so as to reinforce the receiver at the juncture of the stampings. While I have shown the receiver mounted on legs 20, it is obvious that the legs 20 may be omitted.

A plurality of motor-compressor mounting

brackets 22 are supported on the upper stamping 18 as best shown in Figure 1. The motor-compressor unit 14 is provided with conventional spring type mounting members 24 which may be secured to the mounting brackets 22. Condenser supporting brackets 26 are likewise secured to the brackets 22 and serve to support the condenser in proper relationship to the receiver 10. An air circulating fan assembly 30 is held in place by the sheet metal straps 31 which are secured to the brackets 32 which in turn are secured to the condenser 12. The brackets 26 and 32 are preferably hydrogen brazed or otherwise secured to the pipes 34 which constitute the refrigerant conduits for the condenser 12.

In order to eliminate unnecessary weight and unnecessary cost, the condenser fins 40 have been corrugated at their outer edges as indicated at 42 in Figure 3 so as to strengthen the outer edges of the fins and so as to improve the appearance of the unit. This construction makes it possible to omit the usual protective and decorative grill or screen which is normally used for protecting the fins of condensers which are mounted out in the open. Furthermore, even if something does hit against the side of the unit, the fins which may be bent thereby will not be as noticeable as would be the case with fins having normally straight edges.

A control box 50 has been provided as best shown in Figure 2 within which the necessary controls for the unit are mounted. Access may be had to the control box 50 by removal of the panel 52 which is held in place by means of thumb screws 54. Removal of the panel 52 also gives access to the inner surface of the condenser 12. The fan unit 30 is protected by means of the grill assembly 60 which comprises a grill 62 and a grill frame 64. The frame 64 rests upon the upper edges of the condenser fins 40 and the upper inturned ends of the straps 31 as best shown in Figure 1. A rubber-like gasket is provided at the point of contact between the grill frame 64 and the fins 40. The grill assembly 60 may be omitted in those installations where there is no danger of injury from the revolving fan blades. The fan preferably is arranged to circulate the air downwardly through the grill 62 and by virtue of the fact that the top of the casing of motor-compressor unit 14 is positioned intermediate the top and the bottom of the vertically elongated circular-like condenser 12 a great portion of the circulated air is deflected by the casing of unit 14 laterally over convolutions 34 of the condenser coil. By circulating the air downwardly in lieu of upwardly, the condenser remains cleaner longer since the dust which normally collects on the floor is not pulled into the condenser by the air stream. A portion of the air circulated by the fan will sweep the outer walls

of the motor-compressor unit 12 and the receiver 10 so as to cool the same.

The motor-compressor unit 14 is of the type shown in the patent to Francis I. Rataczak No. 2,420,442, dated May 13, 1947, to which reference may be made for a detailed description of the internal construction of the unit. Reference numeral 70 designates the suction line leading from the evaporator 72 to the inlet of the compressor. The compressed gas is discharged directly from the compressor through the discharge line 74 which is connected to the upper pass or convolution of the condenser 12 which serves as a superheat removing coil for partially cooling the compressed refrigerant before it is discharged into the upper end of the motor-compressor housing via the line 76. The partially cooled refrigerant carries along with it a certain amount of lubricant which is dropped out from the refrigerant within the motor-compressor housing before the compressed gas is returned to the second and subsequent passes or convolutions of the condenser 12 via the outlet line 78. The last pass or convolution of the condenser discharges into the receiver 10 via the connection 80 (see Fig. 2). The liquid refrigerant flowing to the evaporator 72 leaves the receiver through the liquid line 82 within which there is provided a conventional pressure reducing means 84 ahead of the evaporator 72.

By virtue of the above described arrangement, it is apparent that the parts of the condensing unit are very compactly arranged and do not require expensive framework for holding the parts together. Thus, the condenser which is supported by the receiver, supports the air circulating fan and the fan grill.

While the form of embodiment of the invention as herein disclosed constitutes a preferred form, it is to be understood that other forms might be adopted, as may come within the scope of the claims which follow.

What is claimed is as follows:

1. Refrigerating apparatus comprising in combination; a stamped sheet metal annular base member having an inner and an outer reinforcing flange; circular condenser means carried by said base member; motor-compressor means including a housing therefor disposed centrally of said condenser means and carried by said base member; means for flowing a cooling medium in thermal exchange with said condenser means and said motor-compressor housing; said base member having a hollow portion constituting a receiver for refrigerant condensed in said condenser means; and refrigerant flow connections between said motor-compressor means, said condenser means and said receiver; said refrigerant flow connecting means comprising first means for conducting compressed refrigerant from said motor-compressor unit into a first portion of said condenser means, means for conveying refrigerant leaving said first portion of said condenser means into said motor-compressor housing, means for conveying refrigerant from said motor-compressor housing to a second portion of said condenser means, and means for conveying refrigerant condensed in said second portion of said condenser means into said receiver.

2. A refrigerant liquefying unit comprising, a base member including a horizontally disposed annular receiver, means for spacing said receiver above a surface upon which it is to be supported, circular condenser means having its convolutions extending a substantial distance above

said receiver along a vertical axis, a casing located substantially in the center of said vertically elongated condenser means and having a portion disposed in the opening of said annular receiver and spaced from walls thereof, said casing containing a motor and a compressor, means disposed above said casing for circulating air downwardly against and over said casing and said receiver, and the top of said casing being positioned intermediate the top and the bottom of said vertically elongated condenser means for deflecting some of the circulated air laterally over convolutions of said condenser means.

3. A refrigerant liquefying unit comprising, a base member including a horizontally disposed annular receiver, means for spacing said receiver above a surface upon which it is to be supported, circular condenser means having its convolutions extending a substantial distance above said receiver along a vertical axis, a casing located substantially in the center of said vertically elongated condenser means and having a portion disposed in the opening of said annular receiver and spaced from walls thereof, said casing containing a motor and a compressor, means disposed above said casing for circulating air downwardly against and over said casing and said receiver, the top of said casing being positioned intermediate the top and the bottom of said vertically elongated condenser means for deflecting some of the circulated air laterally over convolutions of said condenser means, and a cover for said unit including a grill-like portion for shielding said air circulating means.

4. A refrigerant liquefying unit comprising, a base member including a horizontally disposed annular receiver, means for spacing said receiver above a surface upon which it is to be supported, circular condenser means having its convolutions extending a substantial distance above said receiver along a vertical axis, means for supporting said condenser means in fixed relationship relative to said receiver including bracket means connecting said condenser means and said receiver, a casing located substantially in the center of said vertically elongated condenser means and secured to said bracket means, said casing having a portion positioned in the opening of said annular receiver and spaced from walls thereof, said casing containing a motor and a compressor, air circulating means above said casing for circulating air downwardly against and over said casing and said receiver, means for supporting said air circulating means including bracket means connecting the same to said condenser means, and the top of said casing being positioned intermediate the top and the bottom of said vertically elongated condenser means for deflecting some of the circulated air laterally over convolutions of said condenser means.

5. A refrigerant liquefying unit comprising, a base member including a horizontally disposed annular receiver, means for spacing said receiver above a surface upon which it is to be supported, circular condenser means having its convolutions extending a substantial distance above said receiver along a vertical axis, means for supporting said condenser means in fixed relationship relative to said receiver including bracket means connecting said condenser means and said receiver, a casing located substantially in the center of said vertically elongated condenser means and secured to said bracket means, said casing having a portion positioned in the opening of said annular receiver and spaced from walls

thereof, said casing containing a motor and a compressor, air circulating means above said casing for circulating air downwardly against and over said casing and said receiver, means for supporting said air circulating means including bracket means connecting the same to said condenser means, the top of said casing being positioned intermediate the top and the bottom of said vertically elongated condenser means for deflecting some of the circulated air laterally over convolutions of said condenser means, and a cover supported on said unit including a grill frame above said condenser means and a grill above said air circulating means for shielding the same.

6. A refrigerant liquefying unit comprising, a base member including a horizontally disposed annular receiver, means for spacing said receiver above a surface upon which it is to be supported, circular condenser means having its convolutions extending a substantial distance above said receiver along a vertical axis, the bottom portion of said condenser means having an outer circumference slightly greater than the outer circumference of at least a part of said receiver and surrounding said part of said receiver, means for supporting said condenser means in fixed relationship relative to said receiver including a plurality of brackets connecting said condenser means and said receiver, a casing located substantially in the center of said vertically elongated condenser means, means for securing said casing to said brackets including resilient mounting means, said casing having its lower portion positioned in the opening of said annular receiver and spaced from walls thereof, said casing containing a motor and a compressor, a second motor above said casing operatively connected to a fan for circulating air downwardly against and over said casing and said receiver, means for supporting said fan motor from said condenser means, the top of said casing being positioned intermediate the top and the bottom of said vertically elongated condenser means for deflecting some of the air circulated by said fan laterally over convolutions of said condenser means, and a cover for said unit including a grill-like portion for shielding said fan.

7. A refrigerant liquefying unit comprising, a sealed casing containing a motor and a compressor, a heat exchanger including two conduit portions, said conduit portions of said heat exchanger being secured together by a plurality of spaced apart fins to provide a unitary structure in which said fins serve to reduce the temperature gradient between said conduit portions of the structure, each conduit portion of said heat exchanger structure having an inlet and an outlet, refrigerant flow means between said casing and said two conduit portions of said heat exchanger structure, and said refrigerant flow means including a conduit for conducting compressed refrigerant from said compressor to the inlet of a first portion of said two conduit portions of said unitary exchanger structure, a second conduit for conveying refrigerant from the outlet of said first conduit portion of said unitary structure into said casing and a third conduit for conveying refrigerant from said casing into a second portion of said two conduit portions of said unitary structure.

8. A refrigerant liquefying unit comprising, a base member including a horizontally disposed annular receiver, a circular heat exchanger including two conduit portions having the convolutions of its conduit portions extending a substan-

5 tial distance above said receiver along a vertical axis, a casing located substantially in the center of said vertically elongated heat exchanger, said casing containing a motor and a compressor, said two conduit portions of said heat exchanger being secured together by a plurality of fins to provide a unitary structure, each conduit portion of said heat exchanger structure having an inlet and an outlet, a conduit for conducting compressed refrigerant from said casing to the inlet of a first portion of said two conduit portions of said unitary heat exchanger, a second conduit for conveying refrigerant from the outlet of said first conduit portion of said unitary heat exchanger into said casing, a third conduit for conducting refrigerant from said casing into the inlet of a second portion of said two conduit portions of said unitary heat exchanger, a fourth conduit for conveying refrigerant from the outlet of said second conduit portion of said unitary heat exchanger into said receiver, means disposed above said casing for circulating air over said casing and said receiver, and the top of said casing being positioned intermediate the top and bottom of said vertically elongated heat exchanger structure whereby said casing deflects some of the circulated air laterally over convolutions of said heat exchanger structure.

9. A refrigerant liquefying unit comprising, a base member, circular condenser means supported upon said base member and having its convolutions extending a substantial distance above said member along a vertical axis, a casing supported from said base member and located substantially in the center of said vertically elongated condenser means in spaced relation thereto, said casing containing a motor and a compressor, means disposed above said casing for circulating air downwardly against and over said casing, and the top of said casing being positioned intermediate the top and the bottom of said vertically elongated condenser means for deflecting some of the circulated air laterally over convolutions of said condenser means.

10. A refrigerant liquefying unit comprising, a base member including a horizontally disposed annular receiver, a circular condenser carried by said base member and having conduit convolutions extending substantially along the vertical axis thereof from a point adjacent the top of said receiver to a point located a substantial distance thereabove, a casing located within said circular condenser, said casing containing a motor and a compressor, means disposed above said casing for circulating air in a downward direction, and the top of said casing being positioned intermediate the top and the bottom of said vertically elongated circular condenser for deflecting some of the downwardly circulated air laterally over convolutions of said condenser.
